UNITED STATES PATENT OFFICE

GEORGES ROLOT, OF BEAUNE, FRANCE

AUTOMATICALLY OPENING PAINT TUBE

Application filed July 21, 1932. Serial No. 623,877.

The present invention has for its object improvements in automatically opening paint tubes.

These improvements relate more particularly to the kind of cases wherein the opening of the cover is obtained, simultaneously with the emersion of the product, by means of two cylindrical tubes, one of which is arranged to swing around and to slide with respect to the other, owing to the displacement of a pusher connected to the shell supporting the paint-stick, this movable tube being provided with a curved slit for receiving a pin fixed to the pusher, and with a helicoidal guiding slit receiving a pin attached to the fixed tube.

The essential particularity of the invention consists in that the movable tube has the purpose to ensure the opening or closing of the cover and, simultaneously, its automatic arresting so as to prevent all undue opening of the case in the bag or pocket.

For this purpose the movable tube is provided with a slit or guide taking along a pin fixed to the cover, and comprising three portions: firstly a straight longitudinal portion permitting the introduction of the cover pin into the guide on assembling the case; secondly a helicoidal portion having the same pitch and the same direction as the helicoidal slit guiding the movable tube with respect to the fixed tube, and acting as safety means against any undue opening of the cover and, thirdly, an inclined portion destined for the opening of the cover.

Consequently the movable tube ensures, in two strokes, the movement of the cover and its fixation in the closed position.

The invention provides finally a simplified attachment of the pusher to the shell supporting the paint-stick and, furthermore, different details put forward in the following description relating to the drawings appended which represent, merely in the way of an example, one embodiment of a paint-case.

In these drawings are:

Fig. 1 a perspective view of a complete, closed case;

Fig. 2 a perspective view of the outer part

or body of the case together with the cover; Fig. 3 a perspective view of the fixed, central, tube;

Fig. 4 a perspective view of the movable tube;

Fig. 5 the fixed central tube with the movable tube arranged thereon, and the paint shell within the fixed tube;

Fig. 6 the tubular surfaces developed, the case being supposed as closed;

Fig. 7 a similar developed view, the case being supposed as open.

The case according to the invention comprises, for example, an outer shell 1 (Figs. 1, 2) of a square section with flat or rounded off angles and consisting of a thin metal which may be silvered, gilded, nickelized or decorated in any suitable way. It is of course possible to shape this outer shell in any other convenient way.

To the shell 1 is articulated the cover 3 by means of two pivots 2 preferably riveted or soldered, this cover swinging toward the rear of the case.

4 is a curved guiding slit in the shell 1, having one pivot 2 as its center and guiding a pin 5 attached to the cover.

Another longitudinal slide 6 guides the stem 7 of a pusher 8.

On assembling the whole the shell 1 is fixed to a turned socket part 9 (Fig. 3) surmounted by a central fixed tube 10 provided with a longitudinal slit 11, opposite to which is placed the slit 6 of the shell 1.

In the tube 10 slides the sleeve or bush 12 supporting the paint-stick and provided with a slit 13 ensuring to its borders a certain elasticity, and with a hole 14 into which engages the stem 7 with its extremity suitably bent back for this purpose.

To the fixed tube 10 is riveted a pin 15 engaging a slit in the tube 16 in a way specified later on.

This tube 16 (Fig. 4) slides on the tube 10 and is provided with three slits.

The first slit serves for guiding the stem 7 and comprises a straight portion 17_a and a helicoidal portion 17_b with a progressive pitch, which portion could be partially perpendicular to the axis, yet for sake of a

diminished friction the helicoidal shape is preferable.

The second slit serves to receive the pin 15 of the central fixed tube 10 and comprises a helicoidal portion 18_a and a straight portion 18_b perpendicular to the axis of the tube.

Finally, the third slit comprises a straight longitudinal portion 19_a destined for introducing thereinto the cover-pin 5 on assembling the case, a helicoidal portion 19_b having the same pitch and the same direction as the portion 18_a, and finally an inclined portion 19_c destined for the opening of the cover.

On assembling the stem 7 of the pusher 15 traverses the slit 6 of the outer shell 1, the slit 17_a of the inner shell 16, the slit 11 in the inner fixed tube 10 and enters the hole 14 of the bush 12, wherein the extremity of the stem 7 is bent to form a hook (Fig. 5).

20. The mode of operation of the assembled case is as follows:

In the closed position of the case (Fig. 6) the pin 5 of the cover 3 is situated in the portion 19_b of the corresponding slit of the inner shell 16 and abuts against this portion so that all rotary motion of the stud 5 around the pivots 2 in the sense of the arrow *f* is impossible, that is to say, the cover cannot get opened. At this time the stem 7 is at the end 30 of its stroke at the bottom of the slit 11.

The stem is at the same time at the bottom of the slit 6 of the outer shell 1. In this position the slit 6 is closed by a full portion of the inner shell 16 owing to a rotation of the 35 latter to the left.

In order to open the case a push is exerted upon the pusher in the sense of the arrow *f*₁ so as to displace the stem 7 within the slits 6 and 11. On doing that the stem 7 acts upon 40 the slit portion 17_b and tends to move the inner shell 16. Now, since the slit portion 18_a abuts against fixed stud 15 of the tube 10, the inner shell 16 is forced to displace itself in the sense of the arrow *f*₂ parallelly to the 45 slit portion 18_a until the slit portion 18_b abuts against the stud 15. The movement of the inner shell 16 is therefore composed of two strokes:

1.—The stem 7 acts upon the inner shell 16 50 in the upward direction, which shell turns and ascends in the sense of the arrow *f*₂ owing to the slit portion 18_a;

2.—The stem 7 arrives at a certain moment nearly to the upper part of the slit portion 55 17_b the stud 15 finding itself at that moment in the slit portion 18_b, the inner shell performing a rotary movement owing to the slit portion 17_b, after which rotation the stem 7 enters the straight slit-portion 17_a of the inner shell 16.

From this moment the stem 7 slides freely in the slit portion 17_a and permits of emergence of the product contained in the case.

During this time the slit 19 of the inner shell 16 displaces itself with regard to the

pin 5 of the cover until the same gets in contact with the slit portion 19_c.

This pin undergoes therefore a push by said portion 19_c whereby the pin is pivoted around the pivots 2 so that the cover gets 70 opened (Fig. 7).

On closing the case the opposite slit-borders act in the contrary way and produce inverse movements of all parts.

It is obvious that the closing or opening 75 of the cover is effected in two strokes. The first stroke corresponds to a certain partial rotation and ascension of the inner shell 16 whereby the pin 5 gets into the slit portion 19_b, or out of the same. The second stroke 80 corresponds to the slit portion 19_c entering into action.

In this way also a safety stop is obtained 85 preventing all undue opening of the case in the bag or in the pocket, and at the same time the slit 6 of the outer shell is obturated in the closed position. Consequently the case is entirely closed when not used.

It is obvious that the case described above 90 merely in the way of an example permits of numerous modifications wth regard to shape and to the details, without departing from the scope of the present invention.

It may be noted that after engagement of the stem 7 into the slit portion 17_a of the inner shell 16 the latter is prevented from turning and from descending and the cover cannot be closed during utilization.

What I claim, is:

1. In a paint-stick case, a central tube, an outer shell, means to fix said tube and said shell, a tube within said outer shell to move on said central tube, a sleeve movable within said central tube to support the paint-stick, a longitudinal slit in said outer shell, a longitudinal slit in said central tube, a longitudinal slit in said movable tube, an inclined portion in the lower part of said latter slit to undergo the push of the pusher-stem, a stud 100 fixed to the central tube, a helicoidal slit in said movable tube to engage said stud, a pusher, a stem on said pusher to traverse all said longitudinal slits and said sleeve and to terminate within the latter with a hooked 105 extremity.

2. In a paint-stick case, a central tube, an outer shell, means to fix said tube and said shell, a tube within said outer shell to move on said central tube, a sleeve within said central tube to support the paint-stick, longitudinal slits in said tubes and said shell, a pusher, a stem on said pusher to traverse said slits and said sleeve, a cover articulated to said outer shell, an inclined lower portion in said longitudinal slit a helicoidal guiding slope on said movable tube for imparting a rotary movement to the same, another slit in said movable tube, comprising three portions, the first portion being straight and longitudinal, the second portion being helicoidal 115 120 125 130

and the third portion being curved and inclined, and a pin fixed to the cover, to be introduced into said first portion on assembling the case.

5 3. In a paint-stick case, a central tube, a socket to support the same and to impede its turning, an outer shell fixed to said socket, a tube within said shell to move on said central tube, a sleeve within said central tube
 10 to support the paint-stick, longitudinal slits in said tubes and said shell, a pusher, a stem on said pusher to traverse said slits and said sleeve, a cover articulated to said shell, an inclined portion on said longitudinal slit of
 15 said movable tube, a helicoidal guiding slit in said movable tube to cooperate with a stud fixed to said central tube, another slit in

said movable tube, comprising three portions, the first portion being straight and longitudinal and serving for the introduction of a pin fixed to the cover on assembling the case, the second portion being helicoidal and having the same pitch and the same direction as said helicoidal guiding slit, for preventing said pin from turning around the axis of its pivots and in this way the cover from getting opened, and the third portion being inclined and curved in the opposite way, to render possible the opening of the cover by the continued rotation of said movable tube on said central tube owing to the stem of the pusher acting on the inclined portion of said longitudinal slit of the movable tube.

GEORGES ROLOT.
